W. O. KING

Des. 157,500

GAME BOARD

Filed Oct. 18, 1948

FIG. 1.

FIG. 2.

INVENTOR:
Walton O. King,
BY Louis Hayka
ATTORNEY.

UNITED STATES PATENT OFFICE

157,500

GAME BOARD

Walton O. King, Mount Clemens, Mich.

Application October 18, 1948, Serial No. 149,169

Term of patent 7 years

(Cl. D34—5)

To all whom it may concern:

Be it known that I, Walton O. King, a citizen of the United States and resident of the city of Mount Clemens, county of Macomb and State of Michigan, have invented a new, original, and ornamental Design for a Game Board, of which the following is a specification, reference being had to the accompanying drawings, forming part thereof.

Fig. 1 shows a perspective view of a game board showing my new design; and

Fig. 2 is a top plan view thereof.

I claim:

The ornamental design for a game board, as shown.

WALTON O. KING.
